UNITED STATES PATENT OFFICE.

THOMAS CLARKSON, OF LONDON, ENGLAND.

HEAT REGULATING OR GOVERNING APPARATUS.

SPECIFICATION forming part of Letters Patent No. 696,799, dated April 1, 1902.

Application filed October 28, 1901. Serial No. 80,320. (No model.)

To all whom it may concern:

Be it known that I, THOMAS CLARKSON, a subject of the King of England, residing at London, England, have invented certain new and useful Improvements in Heat Regulating or Governing Apparatus, (for which I have made application for Letters Patent in Great Britain, under No. 23,794, dated December 29, 1900,) of which the following is a specification.

10 This invention relates to heat regulating or governing apparatus, and is more particularly applicable for use with steam-generators heated by oil, vapor, or similar burners, its object being to enable the burner to be controlled—that is to say, the flame decreased or increased—in accordance with the temperature of the contents of the generator.

15 According to this invention the flame of the burner or burners employed to heat the generator is controlled by the movement of a rod or lever, which is connected in a suitable way to a spindle attached to a diaphragm inclosed in a casing. The diaphragm is acted upon in some convenient manner by a spring or 20 weight, and the pressure or tension, as the case may be, of this spring or the weight may or may not be adjustable, as desired. One face of the diaphragm constitutes the wall of a chamber into which oil, water, or other 25 fluid can be forced by a pump. The plunger of this pump is reciprocated by a rocking arm preferably actuated by the main engine driven by the steam from the generator which is controlled. A special auxiliary engine may, if 30 desired, be employed, so that the operation of the regulator may be insured and the temperature of the generator controlled when the main engine is not working. A yielding connection is disposed between the pump-plunger 35 and the rocking arm, so that the latter can continue to move without straining the parts when the pump-plunger is held more or less rigidly by mechanism, such as hereinafter described. The arrangement is such that as 40 long as the pump-plunger is held inoperative the flame from the burner will remain unaltered; but as soon as the hold on the pump-plunger is relaxed the rocking arm will cause 45 it to be reciprocated and fluid will be forced into the diaphragm-chamber. The result will 50 cause such movement of the mechanism controlling the burner as to decrease the flame.

When the pump-plunger is again held, the pressure on the diaphragm falls off and the flame of the burner again increases. The 55 pump-plunger is held inoperative or released by a device directly governed by the temperature of the contents of the generator. The essential parts of this device may comprise a substance fusible at a temperature approximating to that at which it is desired to maintain the contents of the generator. In an alternative construction a friction device may be employed actuated by the unequal expansion of metallic members having different coefficients of expansion arranged so that they are subjected to the heat of the contents of the generator.

The arrangement of the pump and mechanism for operating it may conveniently be 70 as follows: The plunger of the pump is extended and carries on it two preferably adjustable collars disposed at a suitable distance apart. Between these collars is a sliding collar or sleeve connected to the end of the rocking arm, previously referred to. The sliding collar may be formed on the end of this lever or be carried rigidly thereon, or the end of the lever may be forked and connected to the sliding collar by gudgeon-pins, with which 80 the latter is provided. Where the collar is rigidly connected to the rocking lever, the opening through which the extension of the pump-plunger passes is made of such size as to allow of the radial movement of the collar 85 when the rocking arm is in motion, the extension of the pump-plunger through this collar always being maintained in a straight line. If desired, however, the extension of the pump-plunger may be pivotally connected to 90 the end of the plunger itself, the sleeve being pivotally carried on the end of the rocking arm and being made a sliding fit on the extension of the plunger. Between the sliding collar and the fixed collars are arranged 95 coiled springs. These may be helical, conical, or otherwise arranged. The ends of these springs conveniently rest in recesses formed in the fixed and sliding collars. The arrangement is such as to enable the pump-plunger to be reciprocated by the rocking arm 100 so long as the pump-plunger is not held against this movement by a device such as previously referred to. When the pump-

plunger is held inoperative, the yielding connection allows the rocking lever to continue its movement without straining the parts. It will be seen that this yielding connection 5 limits the amount of pressure which can be applied to the diaphragm through the fluid forced into the diaphragm-chamber by the pump.

The pump when in operation draws fluid 10 from a suitable reservoir and forces it into the diaphragm-chamber. A by-pass is arranged between the passage leading from the pump to the diaphragm-chamber and the reservoir, a suitable valve or cock enabling the 15 amount of liquid passing through this by-pass to be adjusted. This by-pass enables the pressure which the pump will cause to be exerted on the diaphragm to be adjusted, and also allows the fluid in the diaphragm-chamber 20 to flow back into the reservoir.

An air vessel may, if desired, be situated in connection with the passage between the pump and the diaphragm-chamber. A second by-pass may be arranged between the air 25 vessel and the diaphragm-chamber, this by-pass being controlled by a suitable valve or cock, which can be set as desired. This cock may be so arranged as to also control the lift of the delivering-valve of the pump. This 30 by-pass is designed to prevent rapid fluctuation or pulsations of pressure in the diaphragm-chamber.

A form of device where a fusible substance is employed to effect the holding of the pump-plunger may be as follows: A receptacle of 35 suitable construction and shape is subjected to the heat of the contents of the generator. The receptacle contains a fusible substance, which may conveniently be some alloy or 40 metal. Projecting into this fusible substance is a peg or suitably-shaped piece carrying a lever-arm. The free end of this arm is connected to the pump-plunger. A convenient arrangement is to lead the contents of the generator through a tube coiled helically, metal being cast around this helical coil, so as to enclose it in the wall of the receptacle. The interior of the receptacle may be cylindrical, 45 polygonal, or otherwise shaped, and the peg 50 or plug adapted to lie within it may be either cylindrical, polygonal, fluted, ribbed, or otherwise shaped, as found most suitable. The peg may be formed solid or may be hollowed out in order to increase the hold of the fusible substance upon it. Conveniently both the 55 receptacle and peg are cylindrical, the one having a moderately-loose fit within the other. In this construction a thin skin of fusible substance can lie between the peg and the 60 wall of the receptacle, this thin skin combining with the hold which the fusible substance obtains upon the lower end of the peg or upon its interior when formed hollow to grip the peg and maintain the lever, and consequently 65 the pump-plunger, immovable. It is desirable to prevent air or dirt from gaining access to the fusible substance contained in the re-

ceptacle. To effect this, the peg may conveniently be provided at its outer end with a flange, upon which is a downwardly-directed 70 circumferential rib or ridge adapted to lie within a corresponding annular groove formed in the top of the receptacle containing the fusible substance. In this groove is preferably disposed a small quantity of the fusible substance, which thus forms an air-lock 75 around the peg. The lever previously referred to may be attached to the outer end of the peg in any convenient manner.

The type of generator to which this apparatus is particularly applicable is that in which the water is forced into one of a continuous tubular conduit, steam being drawn from the other end. The coil situated in the wall of the receptacle containing the fusible substance is included in this conduit, so that the contents of the generator continually pass through this coil. Thus the receptacle is maintained at the same temperature as that of the contents of the generator at that part 85 of the conduit in which the regulator-coil is introduced. So long as this temperature is below the desired limit, the fusible substance remains in a solid state, the rocking lever connected to the peg is rigidly held, and the pump 90 thus maintained inoperative. As soon as the temperature limit is reached or exceeded the substance is fused and the rocking lever set free, with the result that the pump commences to work, and in consequence of the pressure 95 of the fluid in the diaphragm-chamber the burner is controlled in the manner above described.

In the case where a friction device is employed to hold the pump inoperative the lever connected to the pump-plunger may be mounted on a peg, which fits within a casing of suitable metal which is subjected to the heat of the contents of the generator in some convenient manner. This may be effected by 105 jacketing the casing or leading a coil of tube through it, as in the case of the receptacle above referred to for containing a fusible substance. In this construction the expansion of the metal and consequent increase in the 110 diameter of the orifice is relied on to release the plug and allow the lever and pump-plunger to be moved. When the temperature falls, the decrease in the diameter of the orifice within which the peg lies causes the peg 115 to be gripped and held by the friction, so as to prevent the lever and pump-plunger from moving. The peg may be cylindrical, the casing being correspondingly shaped; but a convenient construction is to make the peg 120 conical, the orifice in the casing being similarly formed. The peg is so mounted that it can be adjusted axially, this adjustment enabling the apparatus to be set in accordance 125 with the temperature at which it is required to become operative—that is to say, the temperature at which the peg will be released and the pump-plunger allowed to be reciprocated.

In another construction of friction device

hinged jaws may be arranged to grip the periphery of a disk or drum carried on the pivot-pin of the lever connected to the pump-plunger. The periphery of the disk may be grooved or otherwise formed to increase the gripping-surface. The hinged arms are caused to grip or release the disk owing to the unequal expansion of metallic members connected to these arms, the metallic members being subjected in some convenient way to the heat of the contents of the generator. In one arrangement the metallic members may be formed tubular and disposed one within the other. The outer member may be formed of steel and attached at one end to one hinged gripping-arm, the other member being formed of brass and arranged concentrically within the steel member and attached to the other hinged gripping-arm. The free ends of the two members are rigidly connected together and mounted on some convenient base. If desired, the gripping-jaws may be operated by the movement of members having different coefficients of expansion and arranged in any suitable way.

The friction-device may be otherwise arranged or some known form of friction-clutch may be employed, so as to be operated by metallic members such as above indicated. Where the friction-device is so arranged as to be operated by the expansion of metallic members, as above indicated, it is advisable to dispose a yielding connection of some convenient nature between the members and the friction-device. Any distortion or straining of the members is thus obviated.

This invention has been above described in connection with a steam-generator; but it is to be understood that it may equally well be employed in conjunction with a generator for vaporizing the fuel for consumption in a large oil-vapor or similar burner.

The details of construction may be varied considerably in accordance with the requirements and the machinery with which the invention is to be used.

It will be appreciated that the above-described regulating or governing apparatus may be used with one, two, or more burners disposed in groups and in conjunction with one or more generators.

The invention is specially applicable for use with motor-vehicles propelled by steam-power.

Referring to the drawings, Figure 1 is a sectional plan, and Fig. 2 is a sectional side elevation, of a burner-controlling apparatus constructed in accordance with my invention. Fig. 3 is a sectional elevation on the line X X of Fig. 2. Figs. 4 and 5 are respectively an elevation and sectional end view of a modified construction of locking device. Fig. 6 is a section on the line Y Y of Fig. 5. Fig. 7 is a sectional plan, and Fig. 8 an end view, of a further-modified construction of locking device; and Fig. 9 is a sectional elevation on the line Z Z of Fig. 7.

A is the controlling-rod, B the diaphragm, and C the pump.

Referring more particularly to Figs. 1, 2, 70 and 3, in which I have shown the apparatus applied to a vapor-burner wherein the vapor is delivered from a pipe D by a nozzle E into an induction-tube E', where it acts on the principle of an injector, sucking the air into a closed box, (not shown,) which forms the under part of the burner proper, the free end of the induction-tube is preferably bell-shaped or conical, and the nozzle E is placed centrally of the tube at the commencement 75 of its normal diameter. The point A' of the controlling-rod A is adapted to enter the vapor-delivery orifice E² of the nozzle, so that when the point of the rod is moved into or out of the orifice the quantity of vapor passing into the induction-tube of the burner is decreased or increased. The other end of the controlling-rod or lever is connected to one end of the lever A², carried by a spindle E³, mounted in an extension on the induction-tube, or the controlling-lever may be formed 80 integral with the lever A². The lever A² is fulcrumed coaxially with the lever A² and is provided with a clamping-screw A⁴, by means of which it is secured to the spindle. The lever 85 is moved in one direction by the upward movement of the diaphragm and is returned to its normal position by means of a spring A⁶, connected to an extension A⁵ of the lever A². The free end of the lever A² rests on the top end 90 of a spindle F, situated within the diaphragm-chamber B' and having its upper end projecting through the casing thereof. At its lower end the spindle F carries or bears against a piston or plunger F', which rests on the diaphragm B and is adapted to slide up or down in the casing along the diaphragm. The pump-barrel communicates, by means of a 95 conduit C', with a valve-chamber, in one end of which is seated the lift-valve of the pump, 100 consisting of a non-return ball-valve C⁴. This end of the chamber communicates with the reservoir C⁵ through a tube C⁶. In the other end of the valve-chamber is situated the delivery-valve of the pump, which also consists 105 of a non-return valve C³. This end of the chamber communicates with the under side 110 of the diaphragm. In operation the pump draws oil or other fluid from the reservoir and forces it into the diaphragm-chamber beneath 115 the diaphragm, thereby forcing the diaphragm upward against the action of the spring G, which when the pump stops working returns the diaphragm to its normal position. A by-pass passage C⁷ is provided between the end 120 of the valve-chamber, communicating with the diaphragm-chamber and the reservoir, and in this passage is arranged a regulating-valve C⁸, by which the amount of liquid passing through the by-pass passage to the reservoir 125 may be controlled. The end of the pump-plunger is extended and carries at its outer end two collars C⁹ C¹⁰, one of which, C⁹, is adjustable on the threaded part of the plunger 130

and is provided with a lock-nut C^{11} ; but, if desired, both collars may be adjustable. Between the collars C^9 and C^{10} is situated a sliding collar C^{12} , connected to a lever H , the other end of which is fulcrumed at H' to a suitable support, or the sliding collar may be provided with gudgeon-pins and the lever H formed with forked ends to engage with the pins. At a point H^2 intermediate of its ends the lever H is connected to a rod H^3 , by means of which it is rocked. Between the collars C^{12} and the collars C^9 C^{10} are placed conically-coiled springs C^{13} C^{14} , by means of which the rod H is yieldingly connected to the pump-plunger, so that when the plunger is locked the lever is free to be rocked without straining the parts. When the plunger is released, the rocking motion of the lever is transmitted through the springs to the collars on the plunger, whereby the pump is operated.

To the fixed collar C^{10} is pivoted one end of the locking-lever I , the other end of which carries a hollow plug I' , disposed in a chamber or receptacle I^2 , surrounded by insulating material I^3 . A film or skin I^4 , of fusible metal, is placed between the outer periphery of the plug and the inner walls of the receptacle, and a body of fusible metal may also be placed within the hollow plug, which metal obtains a hold on the inner walls and end of the plug and on the end of the receptacle. In order to prevent dust or grit from gaining access to the fusible metal, a flange I^5 is formed at the outer end of the plug and is provided with a downwardly-extending annular lip or ridge I^6 , adapted to lie in a corresponding groove on the top of the receptacle I^2 . A small quantity of fusible metal is placed in this groove and coöperates with the lip to form an airtight lock. The chamber is jacketed or surrounded by a heating-space I^7 , to which the contents of the generator have access, entering the space by the pipe I^8 , and after traversing the chamber leave it by the pipe I^9 , or the contents of the generator may be led around the chamber to a coiled helical tube, or other means whereby the chamber is subjected to the heat of the contents of the generator may be employed.

The locking-lever may be formed separate from the plug, and the flange may be constructed of an independent piece of material from either the plug or the lever. The rocking lever H is constantly tending to reciprocate the pump-plunger, which is normally held inoperative by the locking-lever I . If the temperature within the generator is raised by the heat from the burner above a predetermined limit—that is to say, above the limit at which the metal in the chamber I^2 is fused—the plug is released and the lever I permitted to oscillate with the pump-plunger. The pump then sucks fluid from the reservoir and forces it against the under side of the diaphragm, which is lifted against the action of its spring and operates the levers A^3 A^2 ,

whereby the sharp end of the controlling-rod projects into the nozzle and reduces the amount of fuel or vapor passing through the burner-orifice.

In Figs. 4, 5, and 6 a frictional locking device operated by the unequal expansion of metallic members is shown. In this case the locking-lever I is provided with a tapered part fitting into a recess or opening J' in a projection J^2 of the plug J . The plug is preferably conical and fits a corresponding conical orifice J^3 in the casing J^4 , which is jacketed to form a space J^6 , to which the contents of the generator have access. The casing is preferably formed of bronze or other similar metal and the plug of steel. Other metals, however, having different coefficients of expansion may be employed. Instead of being jacketed the casing may be surrounded by a coil to which the contents of the generator have access. With this arrangement when the temperature within the generator rises above the predetermined limit the casing J^4 expands, thereby freeing the plug and permitting the locking-lever to oscillate with the pump-plunger. The end of the plug is extended and provided with a screw-threaded part having an adjustable collar J^5 and nut J^9 . The contents of the generator enter by the opening J^7 and leave by the opening J^8 .

In a modified construction of locking device (shown in Figs. 7, 8, and 9) the periphery of the plug K , which carries the arm I , is adapted to be gripped by jaws L , hinged at L' to a plate L^{10} , which also carries a center bearing L^{11} for the plug. The other ends of the jaws L are connected at L^4 L^5 to the ends of the metallic tubular members L^2 L^3 , arranged one within the other. The end of the inner member is yieldingly connected to one of the jaws L by means of a spring M . The end of the member passes freely through an opening on the jaw and is provided with a collar L^{12} , which bears against the jaw when the members expand. The spring M is placed between the jaw and an adjustable collar or nut L^{13} on the end of the member, and when the tubular members contract the jaw is pressed against the plug by the consequent compression of the spring M , which latter should further contraction of the members take place is further compressed and prevents straining of the parts. The other ends of the metallic members are rigidly connected together by means of a base-piece L^6 . The contents of the generator enter the outer tubular member by means of a pipe L^7 , and after traversing the length of the tubular member enter the inner tubular member through perforations L^8 and finally leave, after traversing the inner tubular member, by means of a pipe L^9 , or, as above stated, any arrangement of tubular members having different coefficients of expansion may be employed. With this arrangement on an increase of temperature within the generator above the predetermined

limit the tubular members expand unequally, thereby causing the jaws to release the plug and allow the pump-plunger to reciprocate.

What I claim as my invention, and desire to secure by Letters Patent, is—

1. In apparatus for governing vapor, oil and similar burners, the combination with regulating mechanism, of a pump operating a fluid which directly actuates the regulating mechanism, a constantly-moving member yieldingly connected to the pump, a locking-arm connected to the pump, a plug on the arm, and a chamber to which the contents of the generator have access, coöperating with the plug to lock and release the arm in the manner and for the purpose set forth.

2. In apparatus for governing vapor, oil and similar burners, the combination with regulating mechanism comprising levers controlling the burner, of a pump, a constantly-moving member yieldingly connected to the pump, a locking-arm, a plug connected to the arm, and a chamber to which the contents of the generator have access and which coöperates with the plug to lock or release the arm, substantially as described.

3. In apparatus for governing vapor, oil and similar burners, the combination with lever-regulating mechanism, of a diaphragm, a diaphragm-chamber, a fluid-reservoir for the diaphragm-chamber, a pump communicating with the reservoir and with the diaphragm-chamber, a constantly-moving lever yieldingly connected with the pump, a locking-arm connected to the pump, a plug on the arm, and a chamber subjected directly to the temperature of the contents of the generator and which coöperates with the plug to lock and release the arm, substantially as described.

4. In apparatus for governing vapor, oil and similar burners, the combination with lever-regulating mechanism, of a flexible diaphragm, a diaphragm-chamber, a fluid-reservoir for the diaphragm-chamber, a pump communicating through valve-controlled conduits with the diaphragm-chamber and the reservoir, a constantly-moving lever yieldingly connected to the pump-plunger, a locking-arm connected to the pump-plunger, a plug on the arm, and a chamber to which the contents of the generator have access, substantially as and for the purpose described.

5. In apparatus for governing vapor, oil and similar burners, the combination with lever-regulating mechanism, of a diaphragm, a diaphragm-chamber, a fluid-reservoir communicating with the diaphragm-chamber through a by-pass conduit, a pump communicating through valve-controlled conduits with the diaphragm-chamber and the reservoir, a constantly-moving lever, resilient bodies between the lever and the pump-plunger, a locking-arm, a plug on the arm, and a chamber coöperating with the plug and to which the contents of the generator have access, substantially as and for the purpose described.

6. In apparatus for governing vapor, oil and similar burners, the combination with lever-regulating mechanism, of a diaphragm, a diaphragm-chamber, a fluid-reservoir communicating with the diaphragm-chamber through a by-pass conduit, a regulating device in the conduit, a pump communicating through valve-controlled conduits with the diaphragm-chamber and the reservoir, a constantly-moving lever, resilient bodies between the lever and the pump-plunger, a locking-arm, a plug on the arm, and a chamber coöperating with the plug and to which the contents of the generator have access, substantially as and for the purpose described. 70

7. In apparatus for governing vapor, oil and similar burners, the combination with lever-regulating mechanism, of a diaphragm, a diaphragm-chamber, a fluid-reservoir, a pump communicating with the diaphragm-chamber and the reservoir, a constantly-moving lever, collars on the pump-plunger, springs between the lever and the collars, a locking-arm pivoted on the plunger, a plug on the arm, a chamber coöperating with the plug and to which the contents of the generator have access, and means between the plug and the chamber for holding the plug stationary, substantially as 85 described. 90

8. In apparatus for governing vapor, oil and similar burners, the combination with lever-regulating mechanism, of a diaphragm, a diaphragm-chamber, a fluid-reservoir, a pump communicating with the diaphragm-chamber and the reservoir, a constantly-moving lever, collars on the pump-plunger, springs between the lever and the collars, a locking-arm pivoted on the plunger, a hollow plug on the arm, a chamber coöperating with the plug and to which the contents of the generator have access, and fusible metal between the plug and the chamber, substantially as and for the purpose described. 100 105

9. In apparatus for governing vapor, oil and similar burners, the combination with lever-regulating mechanism, of a diaphragm, a diaphragm-chamber, a fluid-reservoir, a pump communicating with the diaphragm-chamber and the reservoir, a constantly-moving lever, collars on the pump-plunger, springs between the lever and the collars, a locking-arm pivoted on the plunger, a hollow plug on the arm, a chamber coöperating with the plug and to which the contents of the generator have access, a cap for the chamber, coacting grooves and lips on the cap and the chamber, and means for locking and unlocking the plug controlled by the heat of the contents of the generator passing through the chamber, substantially as described. 110 115 120 125

In testimony whereof I have signed my name to this specification in the presence of two subscribing witnesses.

THOMAS CLARKSON.
